UNITED STATES PATENT OFFICE

2,603,548

REFRIGERATOR CABINET

George C. Harbison, Erie, Pa., assignor to General Electric Company, a corporation of New York

Application August 29, 1946, Serial No. 693,676

4 Claims. (Cl. 312—237)

1

My invention relates to refrigerator cabinets and particularly to an improved arrangement for mounting the cover for the machinery compartment.

In many present day refrigerators the door is supported from the cabinet only by the hinges and, should the refrigerator be dropped during shipment, the entire force of the door must be taken by the hinges. It is an object of my invention to provide a construction whereby the machinery compartment cover is so mounted that the possibility of misalignment of the door during shipment is minimized.

It is another object of my invention to provide an arrangement for the adjustment of the supports of the machinery compartment cover so that the position of the cover may be adjusted to present a uniform gap between the top of the cover and the bottom of the refrigerator door.

The machinery compartment cover is to be held in position by means of resilient latches which engage properly positioned latch strikes. It is another object of my invention to provide an arrangement whereby these latch strikes will be simultaneously adjusted to the proper position whenever an adjustment of the supports for the machinery compartment cover is made.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a front elevation of a refrigerator cabinet provided with a mounting arrangement embodying my invention; Fig. 2 is a view partially broken away taken along the line 2—2 of Fig. 1; Fig. 3 is a sectional view taken along the line 3—3 of Fig. 2; Fig. 4 is a sectional view taken along the line 4—4 of Fig. 1; Fig. 5 is a view partially in section taken generally along the line 5—5 of Fig. 3; Fig. 6 is an elevation view of a portion of the refrigerator cabinet provided with an alternative mounting arrangement for the machinery compartment cover; Fig. 7 is a front elevation view partly in section, showing the mounting arrangement; and Fig. 8 is a side elevation view.

Referring to the drawings, I have shown in Fig. 1 a refrigerator cabinet 1 having a food storage compartment closed by a door 2 and a machinery compartment closed by a cover 3.

2

composed of two parts 4 and 5. The door is provided with a handle 6.

Referring now to Fig. 2, I have shown the refrigerator cabinet provided with side walls 7 and 8 and a back wall, shown at 9 in Fig. 4, all constructed of sheet metal. The bottom edges of the side walls are bent inwardly and upwardly as indicated at 10 and 11 to provide rigidity. Braces 12 and 13 are provided at the rear corners. Angle members 14 and 15 at the front and rear of the cabinet respectively are provided to support the refrigerating machinery. The front opening of the machinery compartment is closed by the cover 3. To provide adequate ventilation of the refrigerating machinery I have constructed the cover 3 with suitable ventilating openings indicated generally by 16.

Referring now to Fig. 3 I have shown details of one form of my improved arrangement for mounting the machinery compartment cover; an arrangement for supporting and leveling the refrigerator cabinet is also shown. A glider support 17 is bolted or welded to a vertical reinforcing member 18, which in turn is secured to the refrigerator cabinet. The glider support 17 is provided with a horizontal portion 19. In order to level the refrigerator cabinet and facilitate moving of the cabinet, an adjustable glider or foot member 20 is screwed into a threaded opening in the portion 19 of the glider support. A similar glider is provided at the other front corner of the cabinet. Movement of these gliders allows raising or lowering of the front of the cabinet and thereby permits the refrigerator cabinet to be properly leveled.

35 The front support 14 for the refrigerating machinery is welded to the glider support 17. The portion 4 of the machinery compartment cover 3 is provided with a reinforcing plate 21 to which is secured a channel member 22. When the machinery compartment cover is in its assembled position the channel member 22 is supported on the upper surface of an adjustable angle bracket or support 23. This bracket is fastened to the reinforcing member 18 by bolts 24 and 25, or any other suitable fastening devices. The bracket 23 is provided with elongated slots 26 and 27 for the purpose of permitting adjustment of the height of the bracket. A second bracket 28, which serves as a latch strike, is connected to the bracket 23 to permit initial adjustment of the position of the strike relative to the bracket 23 in a manner which will be described later. In order to provide for simultaneous adjustment of the vertical position of bracket 23 and strike 28 a cam 29 is rotatably mounted on the reinforce-

ing member 18 by a bolt 30, or any other suitable mounting device. The cam 29 has several flat surfaces at different distances from its center of rotation. Hence by presenting any one of these surfaces to the bottom of the bracket 23 the vertical position of bracket 23 and also of the strike 28, which is secured to bracket 23, may be adjusted. In addition to adjusting the position of the bracket 23 and strike 28 the cam also assists the bolts 24 and 25 in holding the bracket and strike in the adjusted position.

It will be noted that Fig. 4 covers the mounting arrangement at the opposite side of the cabinet from that shown in Fig. 3. However, since similar mounting arrangements are used at each end, the same numerals have been applied to corresponding parts in both figures. Referring now to Fig. 4, it can be seen that the strike 28 is mounted on the bracket 23 by a lip 31 which fits in a hole 32 in the bracket 23 and by a bolt 33 which passes through the strike 28 and the bracket 23. In order to provide for adjustment of the initial position of strike relative to bracket, the strike is provided with a slot 34 through which the bolt 33 passes. The strike can be pivoted to a limited extent about its lip 31 and then finally be clamped in the desired position by the bolt 33. Although a strike which is adjustably mounted on the bracket 23 is shown, the strike may be fixed to this bracket.

From this figure it can be more clearly seen that the machinery compartment cover 3 is constructed of the two separate portions 4 and 5. These portions are connected together by any suitable fastening devices, such as bolts, two of which are indicated as 35 and 36. The front surface of the portion 5 is recessed somewhat from the front surface of the portion 4 in order to provide suitable ventilating openings for the passage of air to and from the machinery compartment. These ventilating openings have been indicated generally by 16 in Fig. 2 and the edge of one such opening is indicated in Fig. 4 by the bent up end 37 of the portion 4 of the machinery compartment cover. In order to latch the cover in closed position a spring strip 38 having an upwardly extending portion 39 is provided. The spring strip 38 is fastened to a channel 40 which is secured at its ends to the inner top and bottom surfaces of the portion 4 of the cover 3. The upwardly extending portion 39 cooperates with the strike 28 to latch the cover in closed position.

The door 2 is shown in Fig. 4 mounted directly above the machinery compartment cover 3. In order to seal the food storage compartment when the door is in the closed position, a sealing gasket 41 is provided. When the door is closed this gasket fits flush against the front surface 42 of the cabinet. The door is supported only by its hinges. In order that any downward shock to the door during shipment will be transmitted to the reinforcing member 18 one or more hard fiber pads 43 are inserted prior to shipment between the lower surface 44 of the door 2 and the upper surface 45 of the machinery compartment cover 3. In order to protect the finish of the door and the cover the pads 43 are wrapped in a soft backing material, such as that sold under the trade-name "Kimpak." It can be seen that any downward force applied to the door during shipment will then be transmitted through the force transmitting members or pads 43, the machinery compartment cover 3, the reinforcing plate 21, channel 22, and the bracket 23 to the reinforcing member 18. The force is fur-

ther transmitted from the reinforcing member through the glider support 17 and the glider 20 to the surface on which the cabinet rests. In this way the shock is taken by the surface on which the cabinet rests, and the possibility of misalignment of the door during shipment is minimized.

Fig. 5 shows a plan view of the supporting and latching arrangement and clarifies the actual details of construction previously described in connection with Figs. 3 and 4. Referring to Fig. 5 the reinforcing plate 21 and the channel member 22 are shown. The channel 40, which supports the spring latch 38, and the upwardly extending portion 39 of this latch are also shown in this figure. A portion of one of the ventilating openings 16 of the cover 3 is illustrated in Fig. 5.

In Fig. 6 I have shown an alternative mounting arrangement for the machinery compartment cover. In this figure there is illustrated a refrigerator door 46 and a machinery compartment cover 47 mounted directly below the refrigerator door. As described in connection with the preceding construction the machinery compartment cover is composed of two sections 48 and 49, which are secured together as in the previous construction to provide ventilating openings for the machinery compartment. The adjustable mounting arrangement shown in Fig. 6 is illustrated as being applied to only one side of the machinery compartment cover, the opposite side of this cover being hinged on the cabinet as indicated at 50. It will be understood, however, that the adjusting arrangement shown in Fig. 7 can be applied to both sides of the machinery compartment cover. Where it is desired to provide maximum support for the door during shipment such an arrangement is preferred. While not shown in Fig. 6 it will be apparent that for supporting the door during shipment to prevent misalignment in accordance with the objects of this invention one or more hard fiber pads, similar to the pad 43 illustrated in Fig. 4, are inserted between the lower surface of the door and the upper surface of the machinery compartment cover in the form of invention disclosed in Figs. 6, 7 and 8.

Referring now to Fig. 7 I have shown a vertical reinforcing member 51 which supports the refrigerator cabinet. The lower portion of the vertical reinforcing member 51 is bent laterally to provide a horizontal portion 52. An adjustable glider 53 is threaded into an opening in the horizontal portion 52 to provide for leveling of the cabinet in the same manner as has been previously described. A rearwardly extending portion 54, as shown in Fig. 8, is used as a support for an angle member 55 upon which the front edge of the refrigerating machinery rests. The angle member 55 is provided with an ear 56 which is welded to the vertical reinforcing member 51 to lend additional support to the angle member 55. A channel member 57 is welded to the underside of the top surface of the portion 48 of the machinery compartment cover. When the machinery compartment cover is assembled in position this channel member 57 is supported on the top surface of an adjustable bracket or support 58. The bracket 58 is secured to the vertical reinforcing member 51 by bolts 59 and 60 or by any other suitable fastening arrangement. A second bracket 61, which serves as a latch strike, is welded or otherwise secured to the reinforcing member 51. The strike cooperates with a latch to hold the machinery compartment cover

in position, as will be described more fully in connection with Fig. 8.

Referring now to Fig. 8 it can be seen that the bracket 58 is provided with inclined slots 62 and 63. These inclined slots are provided so that the height of the bracket 58 may be varied by shifting the position of the bracket relative to the reinforcing member 51 along the slots. In order to latch the cover in closed position, a spring strip 64 having an upwardly extending portion 65 is provided. The spring strip is fastened to a channel 66 which is secured to the lower inner surface of the portion 48 of the machinery compartment cover. The upwardly extending portion 65 cooperates with an inturned portion 67 of the strike 61 to latch the cover in closed position.

While I have shown specific embodiments of my invention, I do not desire my invention to be limited to the particular construction shown and described, and I intend, in the appended claims, to cover all modifications within the spirit and scope of my invention.

What I claim as new and desire to secure by Letters Patent of the United States is:

1. A cabinet for refrigerators having two vertically spaced openings therein, a door for the upper one of said openings, a cover for the lower one of said openings, said door having a horizontal lower surface, said cover having a horizontal upper surface spaced from said lower surface of said door, a vertical cabinet reinforcing member adjacent said lower opening arranged to support the weight of said cabinet, a foot member mounted on said reinforcing member for supporting said cabinet, a support for said cover, and means for mounting said support on said reinforcing member, at least one pad being inserted between said lower surface of said door and said upper surface of said cover whereby shock during shipment is transmitted from said door through said pad and said reinforcing member to said foot member.

2. A cabinet for refrigerators having two vertically spaced openings therein, a door for the upper one of said openings, a cover for the lower one of said openings, said door having a horizontal lower surface, said cover having a horizontal upper surface spaced from said lower surface of said door, a vertical cabinet reinforcing member adjacent said lower opening arranged to support the weight of said cabinet, a foot member mounted on said reinforcing member for supporting said cabinet, a support for said cover, and means for adjustably mounting said support on said reinforcing member, at least one pad being inserted between said lower surface of said door and said upper surface of said cover whereby shock

during shipment is transmitted from said door through said pad and said reinforcing member to said foot member.

3. A cabinet for refrigerators having two vertically spaced openings therein, a door for the upper one of said openings, a cover for the lower one of said openings, said door having a horizontal lower surface, said cover having a horizontal upper surface spaced from said lower surface of said door, a vertical cabinet reinforcing member adjacent said lower opening arranged to support the weight of said cabinet, a foot member mounted on said reinforcing member for supporting said cabinet, a support for said cover having an inclined slot therein, said support being mounted on said reinforcing member, and means extending through said inclined slot for adjusting the position of said support, at least one pad being inserted between said lower surface of said door and said upper surface of said cover whereby shock during shipment is transmitted from said door through said pad and said reinforcing member to said foot member.

4. A cabinet for refrigerators having two vertically spaced openings therein, a door for the upper one of said openings, a cover for the lower one of said openings, said door having a horizontal lower surface, said cover having a horizontal upper surface spaced from said lower surface of said door, a plurality of supporting and adjusting assemblies for said cover, one assembly being arranged adjacent each side of said lower opening, each assembly comprising a vertical cabinet reinforcing member arranged to support the weight of said cabinet and a foot member mounted on said reinforcing member for supporting said cabinet and a support for said cover mounted on said reinforcing member, a plurality of pads being inserted between said lower surface of said door and said upper surface of said cover whereby shock during shipment is transmitted from said door through said pads and said reinforcing members to said foot members.

GEORGE C. HARBISON.
